(57) **CLAIM**

The ornamental design for a toy set, as shown and described.

DESCRIPTION

FIG. 1 is a front, top perspective view of a toy set, showing my new design;

FIG. 2 is a front, top perspective view of a first piece of the toy set;

FIG. 3 is an exploded view thereof;

FIG. 4 is a front, top perspective view of a lower part of the first piece;

FIG. 5 is a front, bottom perspective view thereof;

FIG. 6 is a front view thereof;

FIG. 7 is a rear view thereof;

FIG. 8 is a left side view thereof;

FIG. 9 is a right side view thereof;

FIG. 10 is a front, left axonometric view thereof;

FIG. 11 is a rear, left axonometric view thereof;

FIG. 12 is a front, right axonometric view thereof;

FIG. 13 is a rear, right axonometric view thereof;

FIG. 14 is a front, top perspective view of a second piece of the toy set;

FIG. 15 is an exploded view thereof;

FIG. 16 is a front, top perspective view of a lower part of the second piece;

FIG. 17 is a front, bottom perspective view thereof;

FIG. 18 is a front view thereof;

FIG. 19 is a rear view thereof;

FIG. 20 is a left side view thereof;

FIG. 21 is a right side view thereof;

FIG. 22 is a front, left axonometric view thereof;

FIG. 23 is a rear, left axonometric view thereof;

FIG. 24 is a front, right axonometric view thereof;

FIG. 25 is a rear, right axonometric view thereof;

FIG. 26 is a front, top perspective view of a third piece of the toy set;

FIG. 27 is an exploded view thereof;

FIG. 28 is a front, top perspective view of a lower part of the third piece;

(Continued)

FIG. 29 is a front, bottom perspective view thereof;
 FIG. 30 is a front view thereof;
 FIG. 31 is a rear view thereof;
 FIG. 32 is a left side view thereof;
 FIG. 33 is a right side view thereof;
 FIG. 34 is a front, left axonometric view thereof;
 FIG. 35 is a rear, left axonometric view thereof;
 FIG. 36 is a front, right axonometric view thereof;
 FIG. 37 is a rear, right axonometric view thereof;
 FIG. 38 is a front, top perspective view of a fourth piece of the toy set;
 FIG. 39 is an exploded view thereof;
 FIG. 40 is a front, top perspective view of a lower part of the fourth piece;
 FIG. 41 is a front, bottom perspective view thereof;
 FIG. 42 is a front view thereof;
 FIG. 43 is a rear view thereof;
 FIG. 44 is a left side view thereof;
 FIG. 45 is a right side view thereof;
 FIG. 46 is a front, left axonometric view thereof;
 FIG. 47 is a rear, left axonometric view thereof;
 FIG. 48 is a front, right axonometric view thereof;
 FIG. 49 is a rear, right axonometric view thereof;
 FIG. 50 is a front, top perspective view of a fifth piece of the toy set;
 FIG. 51 is an exploded view thereof;
 FIG. 52 is a front, top perspective view of a lower part of the fifth piece;
 FIG. 53 is a front, bottom perspective view thereof;
 FIG. 54 is a front view thereof;
 FIG. 55 is a rear view thereof;
 FIG. 56 is a left side view thereof;
 FIG. 57 is a right side view thereof;
 FIG. 58 is a front, left axonometric view thereof;
 FIG. 59 is a rear, left axonometric view thereof;
 FIG. 60 is a front, right axonometric view thereof;
 FIG. 61 is a rear, right axonometric view thereof;
 FIG. 62 is a front, top perspective view of a sixth piece of the toy set;
 FIG. 63 is an exploded view thereof;
 FIG. 64 is a front, top perspective view of a lower part of the sixth piece;
 FIG. 65 is a front, bottom perspective view thereof;
 FIG. 66 is a front view thereof;
 FIG. 67 is a rear view thereof;
 FIG. 68 is a left side view thereof;
 FIG. 69 is a right side view thereof;
 FIG. 70 is a front, left axonometric view thereof;
 FIG. 71 is a rear, left axonometric view thereof;
 FIG. 72 is a front, right axonometric view thereof;
 FIG. 73 is a rear, right axonometric view thereof;
 FIG. 74 is a front, top perspective view of a cover of the first piece, the covers of the other pieces being the same as the cover of the first piece;
 FIG. 75 is a rear, bottom perspective view thereof;

FIG. 76 is a front view thereof;
 FIG. 77 is a rear view thereof;
 FIG. 78 is a left side view thereof; and,
 FIG. 79 is a right side view thereof.
